UNITED STATES PATENT OFFICE.

WALTER T. GORTON, OF THE UNITED STATES ARMY, SPRINGFIELD, MASSACHUSETTS.

MACHINE GUN.

Application filed July 11, 1924. Serial No. 725,440.

(GRANTED UNDER THE ACT OF MARCH 3, 1883; 22 STAT. L. 625.)

The invention described herein may be used by the Government, or any of its officers or employees in prosecution of work for the Government, or by any other person in the United States, without payment to me of any royalty thereon, in accordance with the act of March 3, 1883.

The subject of this invention is a machine gun.

10 In mounting machine guns on aircraft, it is customary to mount them in pairs side by side thereby limiting the space available for the guns and their complementary equipment. To facilitate the operations of 15 the guns in such instances, it is desirable to so construct them that they may be operated from opposite sides, that is, one right handed and one left handed so that the cartridge belts may be fed from the inner or more accessible side. To eliminate the necessity for 20 providing both right and left hand guns, it is desirable to construct a gun of symmetrical arrangement so that it may be operated from either side by the interchange of 25 a minimum number of its parts without interfering with the essential operative elements of the gun.

In order to obtain this symmetrical arrangement special provisions must be made 30 in certain features of the gun, which affect principally means for alternate feeding of a cartridge belt which may be of fabric or metallic disintegrating link construction, stripping the links from the cartridge, stopping the cartridge and belt, extracting the cartridge from the belt and ejecting the empty cartridge case. Attachment and operation of a trigger mechanism for releasing the firing pin which will be operable 40 from either side of the gun are embodied in a companion application.

In guns of this class, the belt is fed from one side above the breech mechanism and is ejected from the opposite side. The live 45 cartridge is extracted from the belt, withdrawn, lowered, and inserted into the breech, while the empty cartridge case is ejected through the bottom of the receiver during the lowering movement of the live cartridge. 50 To permit the extraction and ejection of the cartridge from either side of the gun, it is essential to adapt the barrel extension and

the bolt for the functioning of the extractor and ejector during alternate assembly and operation.

To these and other ends, my invention consists in the construction, arrangement, and combination of elements, described hereinafter and pointed out in the claims forming a part of this specification.

A practical embodiment of my invention is illustrated in the accompanying drawings, in which,

Fig. 1 is a longitudinal sectional view of the rear end of a machine gun;

Fig. 2 is a combination of Fig. 1;

Fig. 3 is a plan view of the rear end of the gun shown in section in Fig. 1 partly broken to show the recoil spring and guide;

Fig. 4 is a combination of Fig. 3 with the 70 cover removed;

Fig. 5 is a plan view of the inner side of the cover;

Fig. 6 is a sectional view taken on the line 6—6 of Fig. 2;

Fig. 7 is a perspective of the feed slide;

Fig. 8 is a side elevation of the left belt guide;

Fig. 9 is a plan view of the combined cam and spring;

Fig. 10 is a side elevation of the cam spring;

Fig. 11 is a view in elevation, partly in section, of the belt stop;

Fig. 12 is a sectional view in elevation, 85 partly in section, of the belt feed pawl;

Fig. 13 is a detail view of the rear cartridge stop;

Fig. 14 is a similar view of the front cartridge stop;

Fig. 15 is a detail view of the reversible ejector;

Fig. 16 is a detail view of the link stripper;

Fig. 17 is a plan view of the front cam plate; and

Fig. 18 is a side elevation of the same plate.

Referring to the drawings by numerals of reference—

The receiver is a longitudinal rectilinear box comprising side plates 10, a bottom plate 11, and a top plate 12 riveted together in any suitable manner. The inner surface

of the side plates adjacent their rear ends are formed with vertical grooves 10', (see Fig. 3) for the reception of the tongues of a back plate or a combined back plate 5 and spade grip 13 which is assembled to the receiver by a downward sliding movement and held in place by a latch 13' mounted on the top plate 12. The back plate 13 carries the usual buffer mechanism for absorbing 10 the shock of the recoiling portions.

The forward end of the receiver is closed by a trunnion block 14 (Fig. 2) conveniently riveted to the receiver and bored for the reception of the breech end of a barrel 15 in 15 a close sliding fit. The trunnion block is counterbored and tapped for threaded engagement with the rear of a barrel jacket 16. Connected to the breech end of the barrel is a barrel extension 17 which terminates 20 in a narrowed arm 18 formed with a stud 19. The rear side portions of the barrel extension are slotted as at 17' to receive a corresponding beveled extension 20 of a lock frame 21 and further slotted to receive 25 pins 22 carrying a breech lock 23 which is vertically slidable with respect to the extensions.

The lock frame 21 is adapted for the reception of an accelerator mechanism comprising, a plunger 24 working in a guide 25 of the lock frame and urged forwardly by a spring 26 confined between the guide and the head of the plunger which is reduced to seat in a recess in the stud 19 formed on 30 the arm 18 of the barrel extension, and an accelerator 27, pivotally mounted in the forward part of the lock frame 21 and formed with two fingers disposed on either side of the narrowed arm 18 of the barrel extension. On recoil, the barrel extension imparts its motion to the accelerator which is turned on its pivot to engage a depending rear portion of the bolt transmitting an accelerated motion to the bolt and when the 40 accelerator reaches its extreme backward position it acts as a stop for the barrel extension, causing it to come to rest. In its backward movement, the barrel extension compresses the plunger spring 26, which is 45 locked by engagement of the accelerator with the stud 19, while the extensions of the lock frame 21 engage the breech lock pin 22 to cam the breech lock 23 out of engagement with the bolt. On the counter-recoil the 50 rear of the bolt trips the accelerator and unlocks the barrel plunger which is then free to assist in driving the barrel extension home, which in turn forces the breech lock to be elevated by a cam plate 28 secured to the 55 bottom plate 11.

A breech bolt 29 is reciprocally mounted on the barrel extension and is formed to engage in grooves on the inner sides of the barrel extension. A slot is formed in the 60 lower rear portion of the bolt to receive the

breech lock 23 when in forward position. The elevated right portion of the bolt (see Fig. 6) carries a driving spring 30 working on a guide 31, the rear end of which is held by the back plate 13 while the front end 70 extends through the bolt and carries a pin for retaining a collar 30' confined by and retractable with the bolt to compress the spring. The forward face of the bolt is formed into a T-slot 29' for gripping a 75 cartridge. The bolt is longitudinally bored to reciprocally mount a hollowed firing pin 32, the point of which extends through an aperture in the forward end of the bolt. The firing pin carries a spring 33 confined between an abutment in the forward end of the firing pin and a holding pin 34 passing through aligning slots in the firing pin and seated in a recess in the bolt. The holding pin 34 also retains a sear spring 35 85 which engages a sear 36 slidably mounted in the rear of the bolt to normally depress the same into a transverse groove formed in the upper face of the firing pin adjacent its rear end to hold the firing pin in cocked 90 position when a cocking lever 37 carried by the bolt retracts the firing pin in a well-known manner.

The sear 36 is maintained in locking engagement with the firing pin 32 by a slide 95 38, transversely mounted in the bolt, which rides on an outstanding lug of the sear and which is normally positioned by means of a spring 38' in line with a trip element (not shown) adapted to be mounted on either side 100 of the gun. When the slide is actuated by the trip, a groove 38' cut in the bottom of the slide is aligned with the lug on the sear, whereby to permit the sear to rise when automatically cammed out of engagement with 105 the firing pin 32 through the instrumentality of the firing pin spring 33.

Mounted in the left forward side of the bolt 29 is an extractor having a shank 39, a cam plunger 40 and a claw 41 positioned in 110 front of and in line with the center of the bolt face and adapted to engage the cannelure of a cartridge to withdraw it from a feed belt during recoil. The shank and the claw remain in this position on the left of 115 the bolt irrespective of the direction of feed. The claw 41 carries a symmetrical finger-like ejector 42 mounted to the left of the claw 41 when positioned for right hand feed and seated on a flange 43 of the extractor 120 when reversed for left hand feed. It will be noted that when the ejector 42 is mounted on the flange 43 it will not interfere with the guide 31 during movement of the bolt 29. The barrel extension 17 is formed with an opposite clearance cut 17' to accommodate the ejector in either of the above positions. When the cartridge is withdrawn from the feed belt by the extractor, the ejector partially embraces the cartridge and 130

grips it firmly due to the pressure of its plunger spring 44 to prevent it from falling during the positioning operation.

- The members 41 and 42 are constrained to perform the above operations by cams 45 and 46 riveted to the receiver and a combined cam and spring 47 carried by the cover. As the bolt moves rearwardly on recoil it carries with it the extractor and a live cartridge, 10 the cam plunger 40 riding over the bevel of the cam 46 (see Fig. 18) to compress the plunger and the extractor continuing in an approximately horizontal path and being prevented from dropping by the pressure of 15 the cam plunger 40 until it is depressed by the cam 47 to insert the cartridge in the T-slot 29' of the bolt 29. Upon counter-recoil, the cam plunger 40 riding on the under side of the cam 46 is further depressed to position the cartridge in line with the breech, and at the same time causing the ejector to engage the empty cartridge case and force the same out of the T-slot when it is free to drop through the bottom of the receiver. 20 When nearing completion of the forward movement, the extractor is forced upward by the cam 45 to position the claw 41 on the next live cartridge and held in contact therewith by the cam spring 47. It will be understood that the empty cartridge case is extracted from the breech by the gripping action of the T-slot.

The cover 48 is hinged to the forward end of the receiver, its free end being engageable by the latch 13'. The inner surfaces of the sides of the cover are longitudinally grooved to reciprocally mount a reversible cam plate 49 formed with a pair of apertures 49', each of which irrespective of the adjustment of the cam plate for right or left hand operation will be in position to receive a corresponding lug 50 formed on the front end of the elevated right portion of the bolt 29, whereby the cam plate and the bolt may be moved in unison. The rear end of the combined cam and spring 47 previously referred to is conveniently mounted in the cover as shown in Fig. 1, while the front end is receivable in the rearmost of a pair of depending guides 51 formed transversely on the cover intermediate its ends. The depending guides 51 are formed with grooves to slidably receive a flanged feed slide 52 of sufficient width to permit entry of a cartridge belt from either end and formed with opposite pairs of apertures 53 to pivotally mount a feed pawl 54 which may readily be disposed upon either end of the slide to provide for alternate feeding of the cartridge belt. An upstanding lug 55 formed on the top of the feed slide is engageable in the cam plate 49 whereby the feed slide may be moved transversely of the gun to position a new cartridge in line with the extractor when the bolt and cam plate are moved rear-

wardly upon recoil and to cause the feed pawl to ride over the belt and next cartridge on the reverse or forward movement.

Riveted to the forward portions of the side plates 10 are similar belt guides 56, 70 each formed with a bracket 57. The guides are suitably slotted for the reception of front and rear cartridge stops 58 and 59, a stop dog 60 or a filler 61 therefor, and a link stripper 62, all of which are mounted on a split pin 63 carried by the bracket. The link stripper 62 is seated in a groove formed in the trunnion block 14, while the cartridge stops rest on the upper face of the block.

For convenience in operating the gun, to load, unload, and correct stoppages, a loading slide 64 formed with a grip handle 65 and working in brackets 66 is connected to the bolt handle 67 which projects through a slot 68 in the side plate and functions in the usual manner.

While in the foregoing there has been illustrated and described such combination and arrangement of elements as constitute the preferred embodiment of my invention, 80 it is nevertheless desired to emphasize the fact that interpretation of the invention should only be conclusive when made in the light of the subjoined claims.

Having thus described my invention what I claim is:

1. A machine gun embodying reversible cartridge feeding mechanism, recoil operated means for operating said mechanism either right or left handed, a recoil spring mounted 100 in said means, a guide for said spring, an extractor and ejector assembly carried by said means and adapted for reversible operation, means for depressing the extractor during recoil movement, a barrel extension engageable by said first mentioned means, said extension provided with opposite clearance cuts, belt guides mounted on both sides of the gun, means for stopping a belt and cartridge, and means for stripping the cartridge from the belt, said stopping and stripping means adapted to be interchangeably mounted on the belt guides.

2. A machine gun embodying a reversible cartridge feeding mechanism, recoil operated 115 means for operating said mechanism either right or left handed, an extractor and ejector assembly carried by said means and adapted to function irrespective of the direction of operation of the cartridge feeding mechanism, a cam spring for progressively depressing the extractor during recoil, belt guides mounted on both sides of the gun, means for stopping the belt and cartridge, and means for stripping the cartridge from 120 the belt, said stopping and stripping means adapted to be interchangeably mounted on the belt guides.

3. A machine gun embodying a reversible cartridge feeding mechanism, recoil oper-

ated means for operating said mechanism either right or left handed, an extractor pivotally mounted in said means, an ejector mountable on either side of the extractor, 5 and a cam spring engageable with the extractor throughout the entire rearward movement of the bolt.

4. A machine gun embodying reversible cartridge feeding mechanism, recoil operated means for operating said mechanism either right or left handed, belt guides mounted on the gun on both sides of the feeding mechanism, each of said guides formed with a plurality of slots, a belt holding pawl, cartridge stops, said pawl and stops mountable in the slots at either end of the guides, and means for extracting and ejecting a cartridge.

5. A machine gun embodying reversible cartridge feeding mechanism, recoil operated means for operating said mechanism either right or left handed, belt guides mounted on the gun at both sides of the feeding mechanism, said guides each formed 25 with a slot, a link stripper mountable in the slot of either of the belt guides, and means for extracting and ejecting a cartridge.

6. A machine gun embodying a cartridge feeding slide, said slide formed with opposite guides to permit entry of the cartridge belt from either side, a reversible feed pawl adapted to be mounted at either end of the slide, recoil operated means for operating said slide either right or left handed, and 35 means for extracting and ejecting a cartridge.

7. A machine gun embodying reversible cartridge feeding mechanism, recoil operated means for operating said mechanism either right or left handed, a spring carried by said means, a guide for the spring, an extractor mounted in said means, and an ejector mounted on either side of the ex-

tractor and adapted to clear the guide during recoil.

8. A machine gun embodying reversible cartridge feeding mechanism, recoil operated means for operating said mechanism either right or left handed, a barrel extension engageable by said means, said extension provided with opposite clearance cuts, an extractor carried by said means, and an ejector mounted on either side of the extractor.

9. A machine gun embodying reversible cartridge feeding mechanism, recoil operated means for operating said mechanism either right or left handed, an extractor and ejector assembly carried by said means, and unitary means for depressing the extractor when in forward position and further depressing the extractor when in rearward position.

10. A machine gun embodying reversible cartridge feeding mechanism, recoil operated means for operating said mechanism either right or left handed, belt guides mounted on either side of the gun, said guides adapted to interchangeably carry means for stopping a belt and a cartridge and means for stripping the belt from the cartridge, and means for extracting and ejecting a cartridge.

11. A machine gun embodying a cartridge feed slide, recoil operated means for operating said slide either right or left handed, a reversible feed pawl carried by the slide for engaging a cartridge, and means for extracting and ejecting the cartridge.

12. A machine gun embodying a reversible cartridge feeding mechanism, recoil operated means for operating said mechanism either right or left handed, an extractor pivotally mounted in said means and an ejector mountable on either side of the extractor.

WALTER T. GORTON.
